UNITED STATES PATENT OFFICE.

HOWARD D. COLMAN, OF ROCKFORD, ILLINOIS, ASSIGNOR TO HOWARD D. COLMAN, LUTHER L. MILLER, AND HARRY A. SEVERSON, COPARTNERS DOING BUSINESS AS BARBER-COLMAN COMPANY, OF ROCKFORD, ILLINOIS.

WINDER.

1,227,754.

Specification of Letters Patent.

Patented May 29, 1917.

Application filed October 31, 1908. Serial No. 460,523.

To all whom it may concern:

Be it known that I, HOWARD D. COLMAN, a citizen of the United States, residing at Rockford, in the county of Winnebago and 5 State of Illinois, have invented certain new and useful Improvements in Winders, of which the following is a specification.

In spinning fibers into yarn, the yarn is wound upon bobbins or the like, each bobbin 10 containing a single thread. If the yarn is to be used as warp it is usual to rewind the yarn from the bobbins onto spools or other containers each of sufficient size to hold a single thread of a length equivalent to the 15 quantity of yarn upon a plurality of bobbins, the threads upon the successively unwound bobbins being tied end to end by the operatives. The spooling machines comprise long frames having series of bobbin-holders and spool spindles arranged along their sides. Whenever a bobbin has been emptied or a thread has broken, or a spool 20 has become full, one of the operatives in attendance on the spooling machine goes to 25 the place where the bobbin or spool is located and there performs the operations necessary to the resumption of winding. Supplies of full bobbins and empty spools must 30 be distributed along the spooling machines, and empty bobbins and full spools removed from various points along said machines.

The object of this invention, generally stated, is to provide a machine of the class referred to in which all of the replenishing 35 operations may be performed in one locality, and to provide mechanical means for performing almost all of said operations.

One of the specific objects of the invention is to provide means whereby bobbins may be 40 fed from a hopper or other suitable receptacle in proper position to automatically enter bobbin holders on the winder frame.

Another object of the invention is to provide means whereby a thread from a full 45 bobbin may be mechanically attached to a thread from a yarn mass on the winder frame.

A further object of the invention is to feed a determined quantity of bobbins from 50 the source of supply at such times as additional bobbins are needed.

Another object of the invention is to provide mechanism for finding the ends of the threads on the bobbins preparatory to uniting them to the free ends of the threads on 55 the receiving yarn masses.

It is also the purpose of this invention to move a spindle out of operative position to prevent rotation of its yarn mass when a thread connection between such yarn mass 60 and a bobbin is broken. It is also the purpose of the invention to supply bobbins to a magazine with corresponding ends first, so that as the bobbins leave the magazine, they will be positioned so as to insure the base or 65 larger ends entering the bobbin holders on the winder frame.

I have also provided means for doffing the bobbins after the bobbin holders have practically completed a cycle of movement on 70 the winder frame. Means is also provided for removing the filled spools and supplying empty spools to empty spindles.

Other objects and advantages of this invention will be apparent by reference to the 75 accompanying drawings when viewed in connection with the description.

The invention will be herein illustrated as embodied in a machine for automatically producing yarn masses upon spools, but it 80 is to be understood that the invention is not limited to spooling and that various features thereof are applicable to other winding operations.

Figure 1— is a diagrammatic plan view 85 of a spooler frame and bobbin supply, a conveyor for carrying the bobbins from the supply to a bobbin ender, thence to a bobbin magazine; means being illustrated, diagrammatically, in this view for feeding spools to 90 the spindles, for removing the filled spools, for doffing the empty bobbins for supplying full bobbins, and for performing other operations.

Fig. 2— is a plan view of the head end of 95 the spooler frame, the doffer for the bobbins and the bobbin magazine with its appurtenances.

Fig. 3— is a side elevational view of the head end of the machine showing part of 100 the bobbin magazine, spool doffer and thread placer actuating mechanism.

Fig. 4—is a plan view of the bobbin magazine, the thread placer and part of the actuating mechanism as well as the conveyer for moving the threads to be united up to the uniting mechanism.

Fig. 5—is a side elevational view of a portion of the magazine and the end finder mechanism looking in the direction opposite to the side shown in Fig. 3.

Fig. 5^a— is an enlarged view of the Geneva stop mechanism for operating the uniting mechanism, the view being taken in the plane of dotted line *a* in Fig. 4.

Fig. 6—is an end view of the hopper for the bobbins and its gate actuating mechanism; the conveyer for carrying the bobbins to the bobbin-end sorter being shown in this view.

Fig. 7—is a side elevational view of the hopper and its gate actuating mechanism.

Fig. 8—is a fragmental side view of the spooler.

Fig. 9—is a plan view of the foot end of the spooler frame showing the chain tightener.

Fig. 10—is a side elevational view of the foot end of the machine.

Fig. 11—is a sectional view on the line "11—11" of Figs. 3 and 8.

Fig. 12—is a fragmentary plan view of a portion of the spooler frame showing the normal position of a spool-carrying spindle when the thread on the bobbin is connected with the thread on its complementary spool. This view also shows the position of the thread detector or feeler for throwing a spindle out of operative position when the thread connection between the spool and the bobbin is broken.

Fig. 13—is an elevational view of the mechanism shown in Fig. 12.

Fig. 14—is a sectional view through a portion of the spooler frame showing a thread running from a bobbin to a spool and in close proximity to the detector.

Fig. 15—is an elevational view of a plurality of spool carrying links and a portion of an equalizer sprocket therefor.

Fig. 21^a is a face view of the bobbin-engaging cup 185.

Fig. 22 (Sheet 2)— is a fragmentary plan view showing the relative positions of the knotter, the thread conveyer and the spool-driving means.

Fig. 23 (Sheet 11)— is a perspective view of the discharge end of the bobbin conveyer 75 and part of the magazine into which it empties.

Fig. 24—is a plan view of the thread uniting mechanism with parts omitted.

Fig. 24^a— is a view of the tying bill and 80 its cam cylinder.

Fig. 25—is a side elevational view of the thread uniting mechanism.

Fig. 26—is an end view of the parts shown in Fig. 25.

Fig. 27—is a plan view of the conveyer for carrying the threads to the uniting mechanism, parts being broken away to show the manner in which the reciprocatory slides are operated.

Fig. 28—is a view partly in elevation and partly in section of a number of connected links forming part of the conveyer.

Fig. 29—is a sectional view through the conveyer and part of its casing.

Fig. 30 is an elevational view of part of the thread placer mechanism.

Fig. 31—is an end view of the thread placer jaws and their operating mechanism.

Fig. 32—is an elevational view of the 100 thread placer jaws in the positions which they assume when closed on the thread.

Fig. 33—is a sectional view through the bobbin-end sorter.

Fig. 34—is a view partly in elevation and partly in section of the bobbin-end sorter, showing a bobbin leaving the sorter to be conveyed to the bobbin magazine.

Fig. 35—is a bottom plan view of the bobbin-end sorter taken in the plane of 110 dotted line 35—35 of Fig. 33.

Fig. 36—is a plan view of the bobbin doffer.

Fig. 37—is a side view of the bobbin doffer.

Fig. 38—is a side view of the bobbin engaging jaws showing them in position to engage a bobbin.

Fig. 39—is a similar view of the jaws showing them separated and about to grasp a 120 bobbin.

Fig. 40—is a sectional view on the line "40—40" of Fig. 38.

Fig. 41—is a sectional view through the bobbin conveying belts associated with the 125 bobbin doffer.

Fig. 42—is a side elevational view of the spool remover.

Fig. 43—is an end view of the spool removing mechanism.

Fig. 44— is a fragmental elevation and Fig. 44^a a sectional view of the spool remover belts and the backing plates therefor.

Fig. 45— is a plan view of a clearer for 5 the thread guides.

Fig. 46 is an elevational view of said clearer.

Fig. 47— is a rear view of the lubricator for applying the lubricant to the empty 10 spindles preparatory to putting on empty spools.

Fig. 48— is a side view of the lubricator.

Fig. 49— is a top view thereof.

Fig. 50— is a vertical longitudinal section 15 view through the lubricator.

Fig. 51— is a sectional view through the lubricator pump.

Fig. 52— is an enlarged elevational view 20 of a portion of the lubricator pump, and the force feed tube.

Fig. 53— is a fragmentary view of the spool feed.

Fig. 53^a— is a sectional view on the line 25 "53^a—53^a" of Fig. 53, part of the spindle throw-out rail being shown in dotted lines.

Fig. 54— is a rear view of the spool feed.

Fig. 55— is a plan view of the spool feed and part of the spooler frame.

Fig. 56— is a view of a portion of the spool 30 conveyer and the spool feed, a spool being shown as entering the said spool feed from the conveyer.

Bobbins carrying yarn which is to be wound onto spools are placed in a hopper 35 "A." This hopper is supported in a suitable frame comprising the standards "60" connected by suitable horizontal bars "61" (Figs. 6 and 7). The bottom of the hopper is provided with an outlet opening having a 40 double gate comprising two slides "62" and "63" respectively. These slides "62" and "63" are intermittently actuated alternately so that a determined quantity of bobbins may be released by the gate 62 to drop upon 45 the gate 63 and from the gate 63 to a vibratory table. The mechanism shown in Figs. 6 and 7 for accomplishing this comprises brackets "64" in which is a shaft "65" carrying a plurality of bell crank levers "66" and "67". The long depending arm of the lever "66" is connected to the slide gate "62" by a link "66", while the long depending arm of the lever "67" is connected to the lower sliding gate "63" by 55 a link "67".

"70" designates a cam shaft having a plurality of cams thereon, one for each of the bell crank levers 66 and 67. The cam "71" actuates the lever "67" through the 60 arm "69" while the cam "72" actuates the lever "66" through the arm "68". By reference to Figs. 6 and 7, it will be observed that the cams "71" and "72" are so disposed on the shaft "70" as to alternately 65 operate the levers "66" and "67". Under

normal conditions, both gates are closed, gate "63" supporting a charge or predetermined quantity of bobbins. Upon actuation of the shaft "70", however, the cam "71" will move the arm "67" so as to open the gate "63" and release a charge of bobbins. Upon further movement of the shaft "70", the gate "63" will be closed by the spring "66^b" and while in the closed position, the gate "62" will be opened to 70 permit a charge of bobbins to fall upon the gate "63" and then the gate "62" will be closed by the spring "66^b" so that the new charge of bobbins will be confined between the gates "62" and "63" until it is necessary 75 to supply more bobbins.

Directly below the hopper A is a vibratory table 79 which receives the bobbins discharged therefrom. The vibratory table is hinged to the frame at "80" by any suitable connection and it is provided at its sides with rails "81" and "82" to guide the bobbins on to an endless carrier to be described hereinafter. The frame carries a beam "83" on which are brackets "84" and "85". The bracket "84" is provided with bearings to receive a transverse shaft "86" on which is a pulley "87". This shaft "86" also carries a bevel gear "88" at one end and a bevel gear "89" at its opposite end. 90 The bevel gear "88" meshes with a bevel pinion "90" on a shaft "91" mounted in the bearings "92", "93" and "94" supported on beam "83".

Mounted in the arm "95" of the bracket "84" is a vertical shaft "96" carrying a bevel gear "97" meshing with the gear "89" on the shaft "86". The shaft "96" drives a horizontal pulley "98" at right angles to the pulley "87". In line with the pulley "87" and carried by shaft "99" is a vertical pulley "100" around which passes a horizontal belt "101" driven from the pulley "87". A belt "102" having its runs in vertical planes or at right angles to the belt "101" passes 105 around a pulley "103" carried by shaft "104" on the arm "105" of the bracket "85". This belt "102" is driven from the pulley "98". The belts "101" and "102" extend adjacent to the discharge end of the vibratory table 110 "79" so that bobbins which are jarred from said table "79" will pass on to the belt 101. As the space between the belt 102 and the lower end of the table 79 is but little more than the diameter of a full bobbin, the travel 115 of the belts 101 and 102 past the table causes any bobbins that are discharged endwise from the table to swing into alignment with the belts. The vibratory table "79" is provided with feet or projections "106" and "107" which rest upon polygonal sleeves or nuts "108" and "109" on the shaft "91". The rotation of the shaft "91" will cause the table to vibrate. While I have shown the nuts "108" and "109" substantially rectan-

120

125

130

gular in cross section, it is obvious that any number of faces may be provided therefor to suit the conditions under which the device is operating. It will be apparent that 5 the belts "101" and "102" and the table are all actuated from the shaft "91", said shaft having on its end a sprocket wheel "110" which receives motion from a chain "111" driven from a sprocket wheel "112" on a 10 shaft "70a" which aligns with the shaft "70" heretofore described. The shaft "70a" is provided with a pulley "113" which is constantly driven. The shaft "70a" is provided with a clutch face "114" to receive a sliding 15 clutch face "115" on the shaft "70" that actuates the gates 62 and 63. The construction of the respective clutch faces may be of any common or preferred form which will cause said shafts "70" and "70a" to remain in 20 clutching engagement during one revolution of the shaft "70a" and then become disengaged.

Means is provided for throwing in the clutch 114-115 when there are no bobbins 25 on the table 79. This means comprises a gage or feeler bar 75 located above and extending longitudinally of the belt 101, said feeler bar having a guide flange 77 and being supported from a shaft 73 by means of 30 arms 74 and 74a and links 76 and 76a. The links extend through guides 83a. The shaft 73 is constantly rocked to raise and lower the feeler bar by means of a cam 120 fixed on the constantly rotating shaft 70a, said 35 cam operating against an arm 119 fixed on the shaft 73. Rigid with the shaft 73 is an arm 118 that overlies one arm of a bell crank 116 pivoted on the bracket 117. The other arm of the bell crank 116 is arranged 40 to operate the detent (not shown) which forms part of the clutch 114-115. A spring 116a normally holds the bell crank 116 in the position in which the detent will throw out the clutch. When the shafts "70" 45 and "70a" are clutched together, the cams "71" and "72" will be actuated in the manner heretofore described so that a charge of bobbins will be released by the sliding gate "63" and after the gate "63" is closed, the 50 gate "62" will open and close to drop a charge of bobbins onto the gate "63" in readiness to be released at the proper time. The vibration of the gage "75" permits the bobbins fed from the table "79" to pass 55 between said gage and the belt "101". The vibratory movement imparted to the gage "75" will be ineffective to throw the clutch face "115" into engagement with the clutch face "114" so long as there is a bobbin be- 60 tween the belt "101" and the gage "75", as a bobbin interposed between the belt "101" and the gage "75" will prevent the gage from moving down far enough to throw in the clutch. The shaft "73" is provided with 65 a depending arm "122" which is connected

to a feeler finger (hereinafter described) co-operating with the magazine "C" for the bobbins and under certain conditions, this arm "122" will prevent the operation of the clutch to cause gates "62" and "63" to operate, even when no bobbins are on the table "79" or on the belt "101". This latter operation, however, will be described hereinafter. 70

As indicated in Fig. 7, the rail 81 terminates short of the lower end of the shaking table 79. Opposite the opening thus provided is a stationary table 79a (Figs. 1 and 7) which is inclined toward the belt 101. The table 79a is covered with material to which yarn will cling. In the event that 75 any of the bobbins are dragged from the table 79 by the bobbins riding upon the belt 101, they will be retarded by the roughened surface of the table 79a until the bobbins on the belt 101 have passed, when they will 80 roll upon said belt. 85

79b (Figs. 1 and 7) designates a guard-rail above the belt 101, and at one side thereof; and this guard-rail, in conjunction with the belt 102, keeps the bobbins in alignment on the belt 101. The guard rail 79b is preferably below the top of the bobbins passing along upon the belt 101 so that should the bobbins crowd upon said belt 101 so as to rest upon one another, the 90 guard-rail will permit the upper one or ones to roll off. 95

The belt 101 discharges the alined bobbins into a trough-like chute 123 which leads to a bobbin-end sorter "B." (Figs. 100 33 and 34.) The bobbin-end sorter "B" is carried by any suitable support and it may consist of a casing provided with the ends "124" and the front and rear sides "125" and "125a" respectively. The bobbin-end 105 sorter has a hopper or flared receiving portion "126" and a tortuous intermediate portion "127" in communication with a discharge chute "128" at its lower end. The portion 127 is made tortuous in order to 110 keep the bobbins in horizontal position. At the juncture of the discharge chute with the tortuous body portion are restricted grooves or openings "129" and "130" (see Fig. 35). The openings "129" and "130" are substantially the same in width, both of these openings being slightly less in width than the diameter of the large end of the bobbin and slightly greater in width than the small or tip end of the bobbin. It will be apparent 115 then that irrespective of which end of the bobbin is first introduced into the hopper "126," the tip of the bobbin must invariably be the end first to enter the discharge chute "128" because as the bobbins drop into the 120 chute 128, the large end of the bobbin will be momentarily retarded while the small end will swing down as shown in dotted lines in Fig. 34. As the small end swings to an approximately vertical plane, the 125 130

large end will be released, permitting the tip end first to drop upon the endless belt or elevator "131" at the end of the discharge chute "128". The endless belt "131" has its upper run incased in a trough-like casing "132" to keep the bobbins on the belt while they are being carried from the bobbin-end sorter to the bobbin magazine into which they are fed. The belt "131" is driven from the pulley "133" (Fig. 23, Sheet 11) at the top of the casing "132" and passes around a pulley "134" at the lower end of the elevator. The pulley "133" is driven by means of a belt (not shown) extending around a pulley 133^a. The belt "131" is provided with transverse cleats "135". The bobbins are fed from the upper end of the conveyer belt "131" into a chute, "136" (Fig. 23) which is in communication with a bobbin magazine "C", the bobbins entering said magazine in substantially horizontal position. The bobbin magazine "C" (Figs. 3, 18 and 19) is provided with a tortuous feed channel "137" in which the bobbins are fed, one upon the other in horizontal planes, to a suitable thread end finder preparatory to feeding them into the bobbin holders on the spooler frame.

By reference to Figs. 18, 19 and 20, it will be observed that at the lower end of the tortuous channel 137 there is an oscillatory valve or gate "138" comprising a tube having a slot "139" therein and depending parallel guide fingers "140" at its respective ends which are adapted to swing with said tube and move the bobbins into and out of contact with the end finder as will be apparent hereinafter. Below the valve 138 is a tortuous guideway passage comprising the guides 141, 142 and 144. The forward or upward movements of the fingers "140" will carry one of the bobbins (for example, the bobbin "x" in Fig. 19) off the guides "141" whereupon said bobbin drops onto the guides "142" so that the return movement of the fingers will permit the bobbin to move down onto devices for lowering the bobbin onto an end-finding brush 143 and for lifting the bobbin from the brush. Said raising and lowering devices comprise a pair of supporting fingers "145" and "146"—(see Fig. 21),—which are rigid with a sleeve 147 that is mounted for oscillation in the supporting framework. These fingers have a slight oscillatory movement imparted to them by a suitable cam so as to raise the bobbin from the end finder after the end has been found or brushed from the bobbin and thus bring the bobbin into line with the top edge of the guides "144." When the fingers "140" swing forward again, that is, from left to right (Fig. 19), the tip end of the bobbin is carried over into the pocket "149" in the side of the casing of the magazine "C" and the butt end of the

bobbin drops through a notch 149^a in the ledge or guide 144 for the bobbin butt, the bobbin dropping thence into the chute 150 butt first for the reason that the pocket 149 and the guard plate 151 (Fig. 18) immediately below said pocket momentarily detain the tip of the bobbin. 70

The contacting surfaces of the end-finder brush 143 and the bobbin rotate in opposite directions, the contacting surface of the brush moving in a direction opposite to the direction of wind of the thread on the bobbin. 75

In suitable bearings in the side walls of the magazine "C" is a transverse shaft 80 "152" (Fig. 20) which is rotated from a sprocket wheel "153" at one end and which is provided at its opposite end with a pinion "154" and a gear "155" (Fig. 5). The pinion "154" meshes with pinion "156" on a 85 stub shaft "157" carried by the magazine casing. The pinion "156" meshes with a gear "158" on a transverse shaft "159" mounted in bearings in the magazine casing, said shaft "159" being provided with a cam 90 "160" at one end, the flange "161" of which imparts a reciprocatory motion to a rod or shaft "148" (Fig. 21) by contact with the roller "162". The rod 148 is rotatably and slidably mounted in the sleeve "147". Adjacent to the cam "160" is a cam "163" which imparts an oscillatory movement to the gate "138" through the medium of the arm "164" with which it contacts. (See Figs. 19 and 20). The cam arm "164" is 100 kept in constant contact with the cam "163" by the spring "164^a", (Fig. 18) one end of which is fast to said arm and it has its other end fixed to the casing. On the end of the shaft "159" opposite to that on which the cam "160" is located and adjacent to the gear "158" is a cam "165", the periphery of which contacts with an arm "166" (Figs. 20 and 21) which is rigid with the sleeve or tube "147". Rigid with the arm 110 166 is an arm 167 which is provided with a bearing "168" in which slides a shaft "169," said shaft being rotatable in a bearing "170" on the bracket arm "171" rigid with the shaft "148". The shaft "169" is provided 115 with collars "172" and "173" to prevent any longitudinal movement of said shaft "169" with relation to the bracket arm "171". The shaft "169" however is permitted to slide in an arm "174" on the sleeve "147" adjacent to the side wall of the magazine "C" and in the arm "167". The shaft "169" is driven from a gear "175" loose on the sleeve "147" which meshes with the gear "176" on the shaft "169" (see Fig. 5). The gear 120 "175" receives its motion from the gear "177" which is rigid with it but which is loose on the sleeve "147" and in mesh with the gear "155" on the shaft "152." On the bobbin-engaging end of the shaft "169" is 125 130

a clutch face having a plurality of spaced bobbin engaging lugs "178" alternating with spaced lugs "179" on the sleeve "180" rotatably carried by the arm "174". (See Fig. 21). The lugs "178" and "179" are adapted to engage the butt of a bobbin. The means to engage the tip of the bobbin is carried by an arm "174a" fixed on the sleeve "147". The tip-engaging means comprises a sleeve "185a" carried by the arm "174a", said sleeve having lugs "185b". Within the sleeve "185a" is slidably mounted a plunger "184" having a cup "185" (Fig. 21a) to center the tip of the bobbin and permit it to rotate therein while the bobbin is being rotated by the clutch lugs 178 on the shaft 169. The lugs "185b" lie in radial slots "185c" (Fig. 21a) in the cup "185". When the shaft "169" and the plunger "184" are moved apart, the lugs 179 and 185b serve to strip the bobbin from the lugs "178" and the cup "185". The plunger "184" is pivoted to one end of a lever "181" which is pivoted at "182" to a stud "183" on the arm "174a".

The other end of the lever has pivotal connection with the shaft "148" at "181a" so that when said shaft is moved from right to left—(see Fig. 21)—the cup "185" will be moved out of engagement with the bobbin as will also be the clutch "178" by the arm "171" at the opposite end of the shaft "148" and the bobbin will be permitted to move onto the guide "144" and be discharged by the fingers "140". A sliding movement of the shaft "169" will not affect its rotation because the gear "175" which drives the gear "176" is of sufficient width to permit a sliding movement of the gear "176" with respect to the gear "175" without throwing said gears out of mesh. A spring "186" (Fig. 21) serves to place the bobbin-engaging jaws in engagement with the bobbin, the jaws being withdrawn by the cam flange "161" (Fig. 20). The parts are so timed that as a bobbin is fed onto the constantly rotating brush "143" the jaw "178" will engage the bobbin and rotate it, whereby the free end of the thread will be brushed off, the thread-end being drawn into a suction tube "190" (Fig. 19). By the time the thread is brushed off, the cam "165" will swing the arms "167" and "174a" upwardly; at the same time the cam "161" is moving the shaft "148" from right to left. Thus, the bobbin is released by its rotating means and is lifted by the fingers "145" and "146" above the upper edge of the guide "144" (Fig. 19) so as to be in a position to permit the fingers "140" to swing it over into the pocket "149".

As the bobbin drops (butt end first) into the chute "150", the found thread passes down a slot 191 that connects the chute "150" and the suction tube "190", the end of said thread remaining in the suction tube. The bobbin remains in the chute "150" until re-

leased by the pivoted gate "191" carried by a bracket "192" on the base plate "193" which supports the magazine. The gate mechanism (Fig. 18a) comprises an arm "194" having an extension "194a" to be engaged by the top of a bobbin-holder on the spooler frame and swing the gate so as to permit the bobbin to drop into the bobbin-holder, butt end first. The arm "194" is carried on a shaft with a segmental gear "191b" meshing with a similar gear "191c" mounted on a shaft to which the gate "191a" is attached. A spring 191d normally holds the gate closed. "191e" is a stop to limit the action of the spring. Up to this point the brushed up or found end of the thread will remain in the slot "191", from which it will be removed and placed in a traveling chain, by means to be hereinafter described. This traveling chain will then carry the end to a uniting mechanism whereby the thread on the bobbin may be united with the thread from a spool on the spooler frame.

The spooler frame "E" is supported on a plurality of standards "196" (Fig. 8) of which there may be a suitable number to correspond with the length of the frame. These standards are connected by longitudinal base rails "197." At suitable points along the rails "197" are castings "198" which support the grooved belt guides "199," (Figs. 12, 13 and 14) the longitudinal edges of which are provided with grooves "200" to receive anti-friction rollers "201" against which the spool rotating belts travel. These belts are driven by suitable pulleys, from a line shafting overhead. The direction of movement of the belts is indicated by the arrow *a* in Fig. 3, the direction of travel of the spools being denoted by the arrow *b*. The first belt from the head of the machine and which I designate "202" (Figs. 1 and 8) passes around a pulley "203" on a standard "204" and around a pulley "205" on a vertical shaft "206." A pulley "207," similar to the one designated "205" is carried by the shaft "206" and drives a belt "208" which passes around an idler pulley "209" on a standard "210" and around a small pulley "211" on a standard "213." (See Fig. 8). The shaft "206" is connected by any suitable connection to a bevel gear "214" which meshes with a gear "215" on the line shaft "216." The ratio of the gears "214" and "215" is such that the pulleys "205" and "207" are driven at relatively less speed than the speed of the shaft "216." All of the remaining belts "217" (Figs. 8 and 10) are on similar pulleys but are driven at the same speed as the speed of the shaft "216" because their driving shafts "206a" are geared with the line shaft by miter gears. It will be observed that the first belt "217" overlaps the

belt "208" and passes around a pulley "218" loosely mounted on the standard "210." The castings "198" also carry supporting rails "219" of which there is one on each side of 5 the spooler frame. These supporting rails terminate short of each end of the frame. (See Fig. 8.) The rails "219" support an endless chain that carries the bobbin holders and the spool spindles. Said chain comprises links "220" (Figs. 12, 13 and 14) 10 which are approximately rectangular and have inwardly projecting arms "221" with hooked ends, which engage the upper edges of said rails "219" and have anti-friction rollers "222" which bear against the face of the rail near the lower edges thereof. These links are in the form of brackets and carry at their outer ends lugs "223" to receive the bobbin holders "195" which may be attached thereto in any well known manner. The form of bobbin-holder herein shown is of ordinary construction and comprises a cradle 195^b (Fig. 18) upon which a bobbin may be rotatably supported, a back-stop 15 195^c, and two side guards 195^a pivoted in the usual manner to a support 195^d and arranged to lie in contact with the yarn mass on the bobbin. The links "220" are provided with slotted projections "225" and 20 "226." Movable vertically in the slots of the projections "225" and "226" are the builder bars "227" which carry thread guides "228" of any preferred form. These builder bars are supported on an undulating 25 rail 229 (Figs. 3, 8 and 10) which is carried by supporting brackets "230" on the base rails "197." In suitable bearings 1 and 2 in the links are mounted shafts 3 each having at its upper end a crank arm 233^a carrying a spool spindle 231 and a collar 232 upon which the spool is seated. Between 30 the bearings 1 and 2, the shaft 3 has a crank portion 233, the cranks 233 233^a being nearly opposite each other. Springs 35 "234" are connected to the cranks "233" at one end and to the links 220 at the other. The crank "233" is so constructed that the spindles will be held on either side of dead center, that is, if the spindle is swung toward the belts "202," "208," or "217" it 40 will remain in contact therewith until mechanically thrown out. If it is swung away from said belts, it will remain away, being held by the spring "234" in either of 45 these positions. The chain composed of the links "220" is driven from the front end by a pair of sprocket-wheels "235" and "236" (Fig. 8) loose on a sleeve "237" (Fig. 16) which is keyed to a gear "238" supported 50 on a column "239" carried by the spooler frame (Fig. 8). The gear "238" is in mesh with a pinion "240" carried on a shaft "241" on the spooler frame and to which is secured a sprocket wheel "242" driven by 55 chain "243" from a sprocket wheel "244" on the shaft "245" which is vertically held in the standard "246." On the upper end of the shaft 245 is a bevel gear "247" meshing with a bevel pinion "248" on the driving shaft "249," said drive shaft "249" having 70 motion communicated thereto by a pulley "250." The drive shaft "249" is journaled in bearings "251" and "252" one of which is carried by the standard "246" and the other by the column "239." It has been 75 stated that the sprocket-wheels "235" and "236" were loose on sleeve "237." These wheels, however, have inwardly projecting lugs; "253" for the wheel "235," and "254" for the wheel "236." (See Figs. 15 80 and 16). These lugs are adapted to be engaged by an equalizing device "255," which is attached to a hub "256" keyed to the sleeve "237"; thus, when a rotary movement is imparted to the gear "238," the 85 sleeve "237" will be rotated carrying with it the equalizing device "255" whose ends will engage the lugs "253" and "254" on the sprocket wheels "235" and "236" so as to rotate them. If, however, the links of the 90 chain have a tendency to bind, one of the sprocket wheels "235" or "236," may slightly over-run the other so as to overcome the tendency to bind and reduce the frictional wear on the parts. The chain passes around 95 the sprocket wheels "257" and "258" (Fig. 10) at the foot end of the machine. The sprocket wheels "257" and "258" are supported in the bracket "204" in ways in the spooler frame and said bracket may be adjusted by the screw "204^b" to tighten the chain. (See Fig. 9). It is to be understood that the belts 202, 208, 217 are driven at a relatively high speed while the chain is driven at a relatively low speed in the opposite direction and that the spindles 231 are normally in such position that the spools engage the spooling belts by frictional contact. Therefore, as the belts are 100 driven, the spools will be rapidly rotated 105 to wind the thread from the bobbins in the bobbin holders upon the spools. If the thread connection between a bobbin and its spool becomes broken, it is desirable to throw the spool out of frictional contact 110 with its driving belt and this is accomplished in the following manner. At suitable points upon the machine I have provided cam arms "259" (Figs. 13 and 14) which are pivoted on the stationary brackets 115 "260." Each cam arm "259" has a lateral extension 261 (Fig. 12) with an inclined or cam face which lies in the path of movement of the collars 232 on the spindles "231." The arm "259," also has a lateral extension 120 "262" which is normally prevented from having a downward movement by the trigger "263" of the pivoted feeler finger 264 as shown in full lines in Fig. 13. 263^a is a 125 stop to limit movement of the trigger in 130

one direction. In view of the fact that the extensions 261 and "262" are rigid with the arm "259," no part of the arm "259" can move unless the extension "262" may move. As 5 the extension "261" with the inclined face is always in the path of the collars "232" on the spindles "231," the engagement of the collars with said extension "261" will throw the spindles away from the belt unless the arm "259" 10 is permitted to swing rearwardly. If the thread connection between the spool and the bobbin is unbroken, the thread will engage the feeler finger "264" as the chain passes along and will swing the trigger "263" on its pivot out of the way of the extension "262" of the arm "259," as indicated in dotted lines in Fig. 13. When this takes 15 place, the extension "261" is free to be moved out of the way by the collar "232" and the operative position of the spindle will be undisturbed. If the thread connection is broken, however, there will be no thread to contact with the feeler finger "264" and the trigger will remain in position to prevent any movement of the arm "259," therefore the extension "261" will be held rigid and instead of the arm "259" moving, the spindle will have to swing in its bearing so as to move the spool away 20 from the belt thus stopping the rotation of the spool.

I shall now describe the mechanism for automatically uniting the thread from a bobbin to the thread on a spool. The uniting mechanism is generically designated by the reference letter "D."

On the base "193" is a bracket "265" (Fig. 30) in which is journaled a shaft "266." This shaft carries a scroll cam "267" and two disk cams "268" and "269" 40 to operate certain thread placing mechanism. This thread placing mechanism is shown in detail in Figs. 30, 31 and 32. The relation of said mechanism to the remainder 45 of the apparatus will be best understood from an inspection of Fig. 2. On the bracket "265" is pivoted a lever "270" having an arm 271 engaging the periphery of the cam "268." The rotation of the 50 shaft "266" imparts an up and down movement to the free end "273" of the arm 270. 275 is a clamping plate and 277 a knife plate, said plates being secured together side by side and being spaced apart by an 55 intervening portion 276. Said plates are connected to the end 273 of the arm 270 by a link 274. A jaw 276^a adapted to enter the space between the plates 275 and 277 is pivoted to said plates at 272, and is rigid 60 with one arm of a lever 278 which is pivoted at 273^a to the arm 270. The other arm of the lever 278 is pivoted to a longitudinally movable arm "279" which has a 65 guide slot "280" at one end and through which projects the shaft "266." The end

of the arm "279" adjacent to the slot "280" is provided with a roller on a lateral projection "281" which engages the groove in the scroll cam 267 so that when said cam is rotated, a longitudinal movement will be 70 imparted to the arm "279" so as to rock the lever "278" and open and close the jaws "275" and "276^a." When the end "273" of the arm "270" is dropped, the jaws will be open as indicated in Figs. 5, 18 and 30, 75 and in the lowered position they are ready to grasp a thread extending from a bobbin which has just escaped from the chute "150" into a bobbin holder "195." It will be remembered that at the time the bobbin 80 slid from chute "150" into a bobbin holder, the found end was still in the slot 191 and held there by the air current in the pneumatic tube "190." The mechanism is so timed that as the bobbin drops into its 85 holder, the jaws "275" and "276^a" close on the thread so that the knife "277" severs it, permitting the surplus thread to be drawn into pneumatic tube "190" through the slot "191." When the thread is thus 90 severed, the strand leading to the bobbin is clamped between the plate 275 and the jaw 276^a. The arms 270 and 279 then swing up, whereby said strand is carried under one of the guards "195^a" (Fig. 18) 95 of the bobbin-holder "195" and then up in a plane above the top of the horizontal pneumatic tube "282" of the tying mechanism "D." This tube is shown in Figs. 2, 4, 5 and 18. After the thread has been thus 100 lifted, it is deflected laterally across the top of the pneumatic tube 282 by a thread placer member "283" (Fig. 4) pivoted to a bracket arm "284" on the base "193," said placer "283" having a crank arm "285" to which is connected a link "286" in engagement with a bell crank lever "287" (Fig. 30) pivoted to the bracket "265" at "288." The arm "287^a" of said lever "287" is arranged to be engaged by the cam "269" so as to give a horizontal sweep to the thread placer member "283" to bring the thread opposite one of a series of openings in the pneumatic tube 282 of the thread uniting mechanism. 1

When the thread has been placed opposite one of said openings, the thread carrier jaws open and then drop beside the chute "150" for a new thread and the member "283" moves back into position shown in Fig. 4 to carry a new thread opposite an opening in the pneumatic tube of the thread uniting mechanism. Two thread-guiding rolls 358 and 359 (Figs. 18, 25 and 26) extend alongside the tube 282. At one end 1 said rolls are supported by brackets 358^a and 359^a. The threads from the bobbins extend over these rolls to the openings in the tube 282. The shaft "266" is provided with a sprocket wheel "289" (Fig. 5) which re- 1

ceives motion through the medium of a chain "290" which passes around a sprocket wheel "291" (Fig. 4) on a shaft "292" of the bracket "293" on the base "193". The shaft "292" is provided with a sprocket wheel "294" from which motion is communicated through a chain "294a" to the sprocket wheel "153" on the shaft "152". This shaft "292" is also provided with a pulley "295" around which a belt "296" passes to drive the pulley "297" on the shaft "187" on which the end-finding brush is mounted. "298" and "299" are idlers to take up slack in the chains "290" and "294a". The shaft "292" carries a sprocket wheel "300" (Fig. 3) around which a chain "301" passes up to a sprocket wheel "302" on a shaft "303" mounted on a bracket "304" supported by the column "239", said shaft "303" receiving motion from the main drive shaft "249" through the bevel gears "308" and "305". The thread uniting mechanism is driven by means of a chain 304a running over the sprocket wheels 300a and 300b. Within the casing "305a" (Figs. 3 and 4) is a polygonal faced wheel "306" having teeth or projections "307" which engage the recesses "308" (Fig. 28) in the links "309" of the chain forming part of the pneumatic tube of the thread uniting mechanism. The links are connected by pintles "310" to form an endless chain, which, in addition to passing around the wheel "306" passes around a polygonal toothless wheel "311" (Fig. 25) in the removable casing "311a", (Fig. 24) which is part of the pneumatic tube "282", and carried on the respective sides of said wheel by the journal "311" are pulleys "312—312". The endless chain moves in grooves in the stationary portion of the pneumatic tube. The tube is closed at its respective ends by the casings "305" and "311a" but is connected with a tube "313" (Fig. 2) which communicates with a fan "314". Said fan is connected to the suction tube "190" through a tube "313a" (Fig. 2).

As shown in Fig. 2, the tube 282 extends between the series of bobbin-holders and the series of spool supports, and its function is to convey pairs of threads (one thread from a newly supplied bobbin and another from the corresponding spool) to the knotter.

At suitable intervals along the chain are links "315" having openings "316" therein which are adapted to be covered and uncovered by slides "317" (Fig. 27) moving transversely in dovetailed grooves "318" in said links. The slides "317" are provided with leaf springs "319" which press against the underside of the links and clamp the threads when the openings "316" are closed. When the links are at the underside of the tube, they are partially closed and remain partially closed as shown in the left-hand portion of Fig. 27 until adjacent to the thread

placer when they open and remain open until they are nearly down to the knotter which forms part of the present thread uniting mechanism. The covering and uncovering of the openings "316" is accomplished by the formation of the grooves in the side walls of the pneumatic tube,—for example—the slide "317" in the left-hand portion of Fig. 27 is shown as having been moved to partially uncover the opening 70 "316" and further movement of the chain in the direction of the arrow will cause the edge "320" of the slide "317" to ride down the inclined face "321" and completely uncover the opening "316". As the links near 80 the knotter, however, a cam face 321a (Fig. 24) similar to the one "321" but on the opposite side of the pneumatic tube, will engage with the edge "322" of the slide "317" and move the slide "317" into closing position to clamp the threads in its opening "316". The threads from the spools are placed over the openings 316 by the operator who finds the ends of the threads on the spools during the time that the spools are 90 passing her. These openings "316" travel at the same rate of speed as the spools and the bobbins. As the thread from a bobbin and the complementary thread from the spool are carried along by the clamp 319, in 95 one of the links "315", they are guided up into position to be operated upon by the knotter (see Figs. 24 to 26) by two members herein shown as consisting of chains "323" and "324" which pass around the pulleys 100 "312" and "312a", around pulleys "328" on the bracket "329" at the top of the pneumatic tube and thence over the pulleys "325" and "326" on the bracket "327". As the two threads are brought adjacent to the knotter, 105 the bobbin thread will be carried up by the chain "323" while the spool thread will be carried up by the chain "324" and they will thus enter the forked end of the stationary guide plate "330" (Figs. 24 and 25) 110 located above the adjacent links and below the tying bill "332". The knotter then begins to operate, the threads being clamped above the tying bill between two stationary jaws "333" and a movable jaw "334", the 115 latter being pivoted at "335". The movable jaw is moved into clamping position by a cam "336" on the cam shaft "337" and is moved out of clamping position by a spring "339". The cam shaft "337" is geared to a 120 driving shaft "340" by the gears "337a" and "340a" (Fig. 24). The driving shaft "340" carries a spiral gear "341" which meshes with a pinion "342" on the shaft of the tying bill, said tying bill being of a construction 125 shown in my Patent No. 755,110, March 22, 1904. As the tying bill completes the knot, the knot is stripped therefrom by a stripper disk 338 fixed on the shaft 337, the united threads being thereafter released through 130

the opening of the clamp 333—334. The united threads then extend across the guides 343 and "343^a" with the knot hanging between the chains "323" and "324" as shown in Fig. 26. The guide 343 and the chains 323 324 are omitted from Fig. 24. During the knot tying operation the ends extending into the pneumatic tube are severed by the tying bill, after which said ends are released 10 through the opening of the clamp 319 by the cam face 321^b (Fig. 24). When released, the cut-off ends are carried away by the suction. When the slide 317 reaches the cam face 321^c (Fig. 24) the slide is moved 15 into the partially closed position, said position being maintained, as hereinbefore stated, until the slide reaches the cam face 321 (Fig. 27). The shaft "340" of the knotter is provided with a bevel gear "340^b" 20 meshing with a bevel gear "340^c" on the drive shaft "340^a". This driving shaft 340^a is intermittently driven through a Geneva stop mechanism so as to actuate the knotter at such times as the threads from the spools 25 and bobbins are in position to be united. The Geneva stop herein shown (Fig. 5^a) comprises a shaft "340^e" provided at one end with a bevel gear "340^f" (Fig. 4) which meshes with a bevel pinion "340^g" on the shaft "340^a" (Fig. 25). This shaft "340^e" 30 also carries a star wheel "340^h" provided with the usual radial slots "340ⁱ" and the peripheral cut out portions "340^j", the edges of which are curved on arcs corresponding 35 to the arc of the periphery of the collar "344^a" on the pin disk "344". The pin disk "344" is on a shaft "345" journaled in suitable bearings and it is provided with a gear "346" which meshes with a gear "347" 40 on the shaft "302^a". Thus, as the shaft "302^a" is rotated the pin disk is actuated so as to engage a slot "340ⁱ" to turn the shaft "340^e" one-fourth revolution at each revolution of its shaft "345". On the shaft "345" 45 is a sprocket wheel 348 carrying a chain which drives a pair of sprocket wheels "349" and "350" (Fig. 5) on two shafts "351" and "352" in the bracket "353". These shafts "351" and "352" carry bevel pinions "354", 50 in mesh with similar pinions "356" on the rolls 358 and 359 (Figs. 25 and 26). These rolls rotate toward the top of the pneumatic tube.

The spool doffer G (Fig. 2) comprises two 55 spool-lifting belts between which the spools are arranged to travel. To bring into line with the spool doffer those spools which have not been moved away from the belts 202, 208, 217 by the cams 261 (Figs. 8 and 60 12), I provide a stationary throw-out rail 354 (Fig. 2) located in position to be engaged by the collars 232 on the spool spindles and thus move the spindles outwardly to a position a little short of dead center. 65 Those spools which have been moved past

dead center by the cams 261 are forced back to the same position as the other spools upon coming in contact with the spool-doffing belts. The rail 354 continues around the head end of the machine and extends to a point opposite the knotter, where it terminates in an inclined end 355 (Fig. 22, Sheet 2). As soon as the thread from a spool and the thread from a bobbin are united, the collar "232" on the spindle "231" 70 moves off the rail "354" and the spool is swung by its spring 234 against a friction plate "356" supported on one of the guides "199". The friction between the spool and the plate "356" will be sufficient to rotate the spool to take up the slack in the thread between the bobbin and the spool. The plate "356" extends a short distance beyond the knotter where it terminates so that the spool may then contact with the driving belt "202" 75 and later with the belt "208" which, as heretofore explained, are driven at a lower speed than the remaining belts. While the spool is in contact with the belts "202" and "208", enough yarn will be wound on the spool and 80 unwound from the bobbin to decrease the diameter of the bobbin and thus let it revolve freely. The necessity for running the spool slowly will, by this time, have been overcome and the spool may be driven at a 85 high speed and may then contact with the belts "217" and continue at the high speed until it returns on the opposite side of the machine, near the head end, when it slows up on meeting the belt 208. The bobbin is 90 then removed and the spool doffed if full, or permitted to pass the doffer in the event that a sufficient amount of yarn is not thereon. The total length of the spool carrying chain and the speeds of said chain and the winding 95 belts may be made to bear such a relation to one another that all the yarn will be removed from the bobbins before they reach the doffing mechanism. The spool doffer comprises two parallel belts 381 and 381^a 100 (Figs. 3 and 43) which are supported by pulleys 372, 373, 380 and 380^a. The pulleys 372 and 373 are mounted on shafts 374 and 375, respectively, which are driven from the shaft 303 through bevel gears 376, 377, 378 105 and 379. The shafts 374 and 375 are supported by the bracket 304. The pulleys 380 and 380^a are mounted in brackets 239^a and 239^b which are fixed to a bracket 239^c on the column 239. Bars 360, 361, 362 and 363 are 110 connected at their lower ends to the brackets 239^a and 239^b and at their upper ends to the bracket 304. These bars serve yieldably to support sectional backing plates 364 and 365 115 for the belts 381 and 381^a, said plates being provided with guide pins 366 and 367 which extend slidably through openings in said bars. On the outer ends of the guide pins 120 are nuts 368 and 369. Between the backing plates and the supporting bars are coiled 125

springs 370 and 371 surrounding the guide pins. The belts 381 and 381^a move in the direction indicated by the arrow in Fig. 43 and they are so positioned that a spool 5 may pass therebetween unless a determined amount of yarn has been wound thereon. If the diameter of the yarn mass on the spool is less than the distance between the belts, the spool will remain on the spindle but if the 10 diameter of the spool is equal to or slightly in excess of the distance between the belts, it will be frictionally engaged thereby and elevated a sufficient distance to remove it from its spindle. It will be noticed that the doffer 15 is so constructed that the belts "381" and "381^a" are inclined from the vertical in the direction of travel of the spools; the speed of the belts and the angle of inclination are so proportioned that full spools will be 20 lifted vertically from the spindles "231" without slipping between the belts. The belts "381" and "381^a" slightly diverge near the top of the doffer so that the spool will be released at a point above the trough or 25 chute "382" whence it may fall into a suitable receptacle provided therefor. The spools not doffed are carried around to the uniting mechanism to have threads from full bobbins united with the spool threads in order 30 that additional yarn may be wound upon the spools so as to bring their diameter up to the required dimension.

I have provided a lubricating mechanism for lubricating the empty spindles and this 35 lubricating mechanism is so arranged that it will not operate when a spool is on the spindle. The lubricating mechanism "H" is best shown in Figs. 47 to 52. At the extreme end of the head of the machine and 40 supported on the column "239" is a bracket "383" in which is journaled a shaft "384" carrying a ratchet wheel "385" and a rotary lubricator pump piston "386" of the gear type and meshing with a piston "387" in a 45 casing "388." The top of the casing "388" is in communication with the force feed tube "389" which holds the lubricant. The bottom of the casing is in communication with a tube "390" having a slit "391" through 50 which the lubricant may be forced. Pivoted to the bracket is a pawl "392" which will slide over the ratchet wheel in one direction but will engage a tooth thereof when moved in the opposite direction so as to hold the 55 wheel against rotation. The shaft "384," the ratchet wheel "385" and the gear "386" are all rigidly connected together. The means for oscillating the pump casing "388" on the axis of the shaft "384" comprises a feeler 60 yoke consisting of two arms "395" and "395^a" and a connecting plate or flange "402." The yoke is pivoted to the bracket "383" at "394." The flange "402" is arranged to be engaged by the heads of spools 65 on the spindles "231." A flange "400" fixed to

the flange "402" has an inclined edge "401" arranged to be engaged by the collar "232" of a bare spindle. A spring "399" tends to swing the feeler yoke inwardly, such movement being limited by the impingement of 70 the reservoir "389" upon the hub that surrounds the axis "394." The connection between the pump casing "388" and the feeler yoke consists of a pin "397" on the casing lying within a slot "396" in the arm "395." 75

Assuming the feeler yoke to be in its extreme inner position, the operation is as follows: The collar "232" on a bare spindle strikes the edge "401" of the flange "400" and forces the feeler yoke to swing outwardly. Such movement causes the pump casing to turn on the axis of the shaft 384. As the shaft 384 and the gear 386 are held by the pawl 392 against rotation, the turning movement of the casing causes the gear 387 80 to turn, whereby a small quantity of grease is extruded from the slot "391." As the collar "232" moves along the edge "401," the spring "399" draws the feeler yoke inwardly, thus placing the slotted portion of the tube 85 "390" in position to wipe the spindle as it passes. If the next succeeding spindle carries a spool, the lower head of the spool engages the flange "402" and prevents the spring "399" from moving the tube 390 into 90 contact with the spools. A pawl-supporting plate 393 secured to the casing 388 holds the pawl away from the ratchet wheel 385 until a predetermined point in the outward swing of the feeler yoke, and thus regulates 95 the amount of lubricant extended from the slot 391.

After the empty spindles are lubricated, it is desirable to supply them with spools and the manner in which this is accomplished is 100 best shown in Figs. 53 to 56 inclusive and at "I" in Figs. 1 and 3. "403" is an endless belt forming an elevator for carrying empty spools up to a tube "404" supported by a bracket "405" on the column "239." The 105 axial center of the discharge end of said tube is in the path of the spindles. Within said tube "404" is an escapement comprising a double tooth dog "406" pivoted to the tube at "407." Said dog is swung on its pivot by 110 link "408" connected to the arm "409" rigid on the swinging yoke "410." The swinging yoke comprises two arms "411" and "412" connected at their bottom ends by a plate "413." Said plate "413" has a cam edge 413^a 115 to bear against the collar of the spindle. As the collar moves along the cam edge (in the event no spool is on the spindle) the spring "414" will swing the lower end of the yoke inwardly from the position shown in 120 Figs. 53 and 54 and actuate the escapement so as to drop the lowermost spool in the tube 404 onto said empty spindle. If a spool is on the passing spindle, however, the lower head of the spool will engage with the flange 130

"415" on the plate "413" and the spring "414" will be ineffective to move the lower part of the yoke inwardly so as to actuate the escapement.

5 It has been stated heretofore that means is provided for removing empty bobbins from the bobbin holders 195. In Figs. 36 to 41, I have illustrated a form of mechanism "F" for accomplishing this. This mechanism 10 is shown as being supported upon a table "416." On the table is mounted a cylindrical member or roller "417" having a double cam groove "418" to receive a shoe "419". This shoe "419" is provided with a crank 15 arm "420", the shaft "421" of which is journaled in a plate "422" which slides in a guide "423" on the table "416". The crank arm "420" is connected to two links "424" and "425" which, in turn, are connected to 20 two elbow arms "426" and "427" pivoted to the plate "422" at "428". To the free ends of the arms "426" "427" are fixed pins "429" "430". A spring "430a" tends to swing the arms "426" "427" toward each 25 other. By reference to Fig. 39, it will be obvious that the relative positions of the fingers "429" and "430" will be determined by the angle of the shoe "419" in the groove "418". The cam is so cut that as the plate 30 422 moves toward a bobbin holder, the two fingers "429" and "430" will be above and below a bobbin in a bobbin holder and when in proper position the fingers will close on the bobbin and the cam will cause the plate 35 to slide so as to draw the bobbin from its holder. When the plate and fingers reach a determined height upon the inclined table "416" the cam will cause the fingers to open and the bobbin will be released. Immediately after this, the plate and fingers will 40 move down into position to grasp another bobbin.

For the purpose of separating bobbins having more or less yarn thereon from bobbins which have been wholly emptied, I provide a plate 451 which is inclined in two directions, *i.e.*, toward the lower end of the table 416 and toward one side of said table. The upper surface of the plate 451 is covered 45 with some material to which yarn will cling. On their upward stroke, the fingers 429 and 430 carry the bobbin onto the plate 451. The fingers then release the bobbin. If the latter has no yarn it slides longitudinally to 50 the foot of the table 416, being discharged at 452 into a suitable receptacle (not shown). If the bobbin was not wholly freed from yarn in the spooler, the yarn clings to the surface of the plate 451 and 55 thus prevents the bobbin from sliding; instead, the bobbin rolls down the plate 451 60 toward the side of the table 416.

To sort the bobbins having yarn into different lots according to the amount of yarn 65 on the bobbins, I provide two endless diverg-

ing belts 431 and 432. The belt 431 moves in a guide 433 (Fig. 41) and passes around pulleys 434 and 435. The belt 432 rest in a guide 436 and it passes around the pulleys 437 and 438. The pulley 434 receives its 70 motion from a pulley 439 having a belt connection with a pulley 440 which is rigid with the pulley 437 and a gear 441. The gear 441 receives its motion from a pinion 442 on a shaft 443. The shaft 443 is provided 75 with a sprocket wheel 444 driven from a sprocket wheel 445 on a shaft 446. The shaft 446 carries a bevel gear 447 that drives a pinion 448 on the cam 417. The shaft 446 is provided with a sprocket wheel 80 449 which is in driving connection with a sprocket wheel 450 (Fig. 8) on the shaft 249.

Bobbins which roll off the plate 451 and onto the belts 431 and 432 are carried up by said belts until the increased distance between the belts permits the bobbins to drop 85 between the belts into suitable receptacles (not shown). Thus the bobbins will be sorted according to their diameter, or, in other words, according to the amount of 90 yarn thereon.

A feeler finger "457" (Fig. 3) is pivoted to a bracket "458" on the magazine "C". Its upper end is prevented from moving into a slot in the tortuous passage "137" by the 95 tension spring "459" and by the presence of bobbins in said passage way. There is a flexible connection, as a wire "460", between the finger "457" and the lever "122" (Fig. 6). The weight of the feeler 75 tends to 100 swing the feeler 457 into the passage 137. Therefore, if bobbins are present in the magazine, so as to prevent the upper end of the finger "457" from entering the slot, the feeler 457 will prevent the arm "118" from 105 swinging far enough to throw in the clutch "114—115" even when no bobbins are on the table "79". Likewise, if there are no bobbins in the magazine "C" and there are some on the table "79", the shaft "73" will 110 be prevented by the gage "75" from rocking far enough to throw in the clutch 114—115. In other words, in order to permit the shaft "73" to throw in the clutch, it will be necessary to have both the magazine "C" at the 115 point where the feeler operates and the table "79" devoid of bobbins.

In Figs. 45 and 46, I have shown a clearer for the thread guides "228". This clearer is shown as a blade "453" pivoted to a 120 bracket "454" at "455". A spring "456" normally holds the blade in position to pass between the lips of the thread guides "228". The position of the clearer with respect to the machine frame will be apparent by reference to Figs. 42 and 43.

As indicated in Figs. 3 and 8, the rail 229 is depressed at the head end of the machine so as to bring the slots in the thread guides 228 in alignment with the blade 453, and so 130

that the thread guides shall be out of the way of the operative during the operation of finding the thread-ends on the spools. After the thread guides have passed the 5 knotter, the thread guides are again reciprocated longitudinally of the spools to lay the yarn thereon.

From the foregoing description, it will be apparent that bobbins may be placed in 10 a hopper and fed to the spooler, where threads of the bobbins are automatically tied to the threads of the spools. After the 15 yarn on the bobbins has been unwound, the bobbins are mechanically removed and placed in suitable receptacles. When filled the spools are automatically removed. The 20 spool spindles are lubricated, and new spools supplied to empty spindles, the entire process being practically automatic, the only 25 manual feature being the placing of the threads from the spools opposite the suction openings, in the links "315". It will be seen that the operative does all of her work while remaining stationary at one point.

25 In certain of the following claims I have used the term "winding couple" to denote two yarn masses, regardless of their size or form, one of which is being rewound on the other.

30 I claim as my invention:

1. A spooler having, in combination, a spooler frame having a plurality of traveling bobbin holders; spool carrying spindles movable with said bobbin holders; means 35 for causing the bobbin holders and spool-spindles to travel; means for rotating spools mounted on said spindles; and means for automatically feeding bobbins to said bobbin holders.

40 2. A spooler having, in combination, a spooler frame; a plurality of traveling bobbin-holders on said spooling frame; means for rotatably carrying a spool opposite each bobbin holder; means for causing 45 the bobbin holders and spool-carrying means to travel; means for rotating spools mounted on said carrying means; means for automatically feeding bobbins to said bobbin holders; and means for automatically 50 removing said bobbins at a determined point with respect to said frame.

55 3. A spooler having, in combination, a frame; spool spindles on said frame; means for rotating the spools on said spindles; a bobbin holder in which a bobbin may lie loose, there being one bobbin holder opposite each spool spindle; and means for feeding bobbins to said bobbin holders.

60 4. A spooler having, in combination, a frame, an endless chain on said frame; means for imparting movement to said chain; bobbin holders carried by said chain; spool supporting spindles carried by said chain; friction devices for contact with the 65 spools to rotate them; and means for auto-

matically feeding bobbins to said bobbin holders.

5. A spooler having, in combination, a frame, an endless chain on said frame; means for imparting movement to said chain; bobbin holders carried by said chain; spool supporting spindles carried by said chain; means for feeding bobbins to said bobbin holders; and means for feeding spools to said spindles. 70 75

6. A spooler having, in combination, a frame, a series of connected bobbin supporting devices carried by said frame and traveling thereon; a series of traveling spool carrying spindles, the movement of said spools being synchronous with the movement of the bobbin supporting devices; means for causing said series of bobbin-supporting devices and spool-carrying spindles to travel; endless belts for rotating said 80 spools; and means for actuating said belts at varying speeds with respect to each other. 85

7. A spooler having, in combination, a frame, an endless conveyer on said frame; means for actuating said conveyer; spool carrying spindles on said conveyer; bobbin holders on said conveyer; means for feeding spools to said spindles; means for feeding bobbins to said bobbin holders; means 90 95 for uniting the thread from a bobbin to a thread from a spool; and means for rotating the spools, the initial rotation of the spools being relatively slow.

8. A spooler having, in combination, a 100 frame; an endless conveyer on said frame; means for actuating said conveyer; means on said conveyer for rotatably carrying spools; means on said conveyer for holding bobbins; thread guides adjacent to the spools; 105 and build-bars for supporting said thread guides, said build-bars having longitudinal movement with respect to the spools.

9. A spooler having, in combination, a frame, a plurality of movable, connected 110 spool and bobbin supporting members carried by said frame; means for causing said plurality of members to travel; means for automatically feeding bobbins to said members; and means for automatically feeding 115 spools to said members.

10. A spooler having, in combination, an elongated frame; a horizontally movable conveyer carried by said frame; means for actuating said conveyer; spool spindles on 120 said conveyer; bobbin carriers on said conveyer; means for rotating the spools; and means for moving the spools away from said rotating means when a thread connection between the bobbin and spools is 125 broken.

11. A spooler having, in combination, a frame; movable bobbin carriers on said frame; movable spindles on said frame; means for causing said carriers and spindles 130

to travel on said frame; means for uniting a thread from a bobbin to a thread from a spool; means for rotating said spools; and means for moving the spools away from 5 the rotating mechanism when the connection between the spool and bobbin breaks.

12. A spooler having, in combination, a frame; a bobbin holder and a spindle; means for causing said holder and spindle 10 to travel on said frame; means for uniting a thread from a bobbin to a thread from a spool on said spindle; means for rotating said spool; and means for moving the spool away from the rotating means when the 15 connection between the bobbin and spool is broken.

13. A spooler having, in combination, a frame; a plurality of traveling bobbin holders carried by said frame; a plurality of 20 spool supporting spindles, one for each bobbin holder; means for causing the holders and spindles to travel; means for feeding bobbins to said bobbin holders; a thread uniter for connecting the thread from a bobbin to a thread from a spool; and means for presenting threads from the bobbins and spools to the thread uniter.

14. The combination of a magazine having a channel therein, down which bobbins 30 may be fed; means for finding a loose thread end on a bobbin in said magazine; means for ejecting the bobbin from the magazine; and means for holding the found thread end.

15. The combination of a magazine having a bobbin guide; an oscillatory gate at 35 the discharge end of said guide; means for finding a loose thread-end on a bobbin; and means for holding said found end when the bobbin is discharged from the guide.

40 16. The combination of a magazine having means for containing bobbins; an oscillatory gate for releasing said bobbins; means for rotating said bobbins; an end finder rotating in a direction opposite to the direction of wind of the thread on the bobbins; and means for moving said bobbins away from the end finder.

17. The combination of a bobbin receptacle, means for releasing the foremost bobbin; means for rotating the released bobbin; a brush contacting with the surface of 50 the rotating bobbin to brush up or find the thread end; and means for ejecting the bobbin after the end has been brushed up.

55 18. The combination of a bobbin receptacle; means for releasing the foremost bobbin; rotatable bobbin-end-engaging-means; means for moving the bobbin-end-engaging-means into and out of engaging position; and a brush to contact with the surface of 60 the bobbin while the latter is held by said engaging means.

19. A spooler having, in combination, a source of bobbin supply; a bobbin magazine; 65 means for feeding the bobbins from the

source of supply to the magazine; a spooler frame; spool spindles and bobbin holders carried by said spooler frame; means for feeding bobbins from the magazine to the bobbin holders; and means for uniting a 70 thread from a bobbin to a thread from a spool.

20. A spooler having, in combination, a source of bobbin supply, a frame having bobbin holders and means for rotating 75 spools; a bobbin magazine; means for feeding bobbins from the source of supply to the magazine; means for feeding bobbins from the magazine to the bobbin holders; means for finding the thread ends on bobbins; and means for connecting the found thread end from a bobbin to a thread end from a spool.

21. A winder having, in combination, a frame, spindles on said frame; bobbin supports carried by said frame, means for rotating yarn containers on said spindles; means for uniting the thread from a bobbin to a thread from one of said yarn containers; and means for doffing bobbins from said 85 bobbin supports.

22. A winder having, in combination, a frame, spindles on said frame; bobbin supports carried by said frame; means for rotating yarn containers on said spindles; means for uniting the thread from a bobbin to the thread from one of said yarn containers; means for doffing bobbins from said 95 bobbin supports; and means for doffing yarn containers from said spindles.

23. A winder having, in combination, 100 means for causing a yarn container and a bobbin to move in a prescribed path; stationary means for uniting a thread from the bobbin with a thread from the yarn container; and means for rotating the yarn container.

24. A spooler having, in combination, means for causing a spool and a bobbin to move in a prescribed path; stationary means for connecting a thread from the bobbin to a thread from the spool; and means for rotating said spool, comprising a belt operatively engaging said spool.

25. A winder having, in combination, 115 means for moving two thread containers in an endless path; means for uniting the thread from one container to a thread of another container; and means for rotating the container upon which the thread is to be wound.

26. A spooler comprising an endless spool and bobbin support; an endless belt for rotating spools on said support; means for driving the belt and means for driving said spool and bobbin support; means for doffing the bobbins; and means for doffing the 125 spools.

27. A textile machine comprising an endless carrier; means for continuously moving said carrier; means on the carrier for 130

supporting bobbins and spools; means for uniting yarn from a bobbin to yarn from a spool; and means for doffing the spools.

28. A spooler comprising a frame, an endless carrier supported by the frame; means for moving said carrier; spool spindles carried by said carrier; means for doffing the spools; and means for lubricating said spindles as they pass a certain point.
- 10 29. A spooler comprising a frame, an endless carrier supported by the frame; means for moving said carrier; means for doffing the spools; means for lubricating the empty spindles; and means for supplying spools 15 to empty spindles.

30. A spooler frame having an endless carrier thereon provided with bobbin holders and spool supporting means; means for moving said carrier; means for doffing the bobbin; means for doffing the spools; means for supplying spools to said spool supporting means; and means for supplying full bobbins to said bobbin holders.

31. The combination of a bobbin receptacle; means for intermittently releasing determined quantities of bobbins; a table to receive the bobbins thus released; means for vibrating said table to discharge bobbins therefrom; means for receiving said 25 bobbins from the table; and means for conveying said bobbins end to end from the table to said receiving means.

32. The combination of a table; means for vibrating said table; means for intermittently feeding a determined quantity of bobbins to said table; means for actuating said feeding means; and bobbin-controlled means for preventing actuation of the feeding means.

40 33. A bobbin-aliner having, in combination, a belt, parts extending longitudinally of the belt at opposite sides thereof to prevent the escape of bobbins from the belt, the space between said parts being but little 45 more than the diameter of a bobbin, means for discharging bobbins onto the belt, and means for moving the belt.

34. The combination with a table, of means for intermittently feeding a determined quantity of bobbins to said table; means for vibrating said table; means for receiving bobbins from said table and for arranging them end to end; and a bobbin end sorter, into which said bobbins are fed 55 from said receiving means.

35. A winder having, in combination, a bobbin magazine; means for ejecting bobbins from said magazine; means for holding a thread end extending from the ejected 60 bobbin; a spool container; means for uniting the thread from the bobbin to a thread on the spool; and means for carrying the bobbin thread to the thread uniting mechanism.

65 36. A bobbin-aliner having, in combina-

tion, a belt, parts extending longitudinally of the belt at opposite sides thereof, the space between said parts being but little more than the diameter of a full bobbin, means for discharging full bobbins from 70 one of said parts onto the belt, and means for moving the belt.

37. A bobbin-aliner having, in combination, a belt, parts extending longitudinally of the belt at opposite sides thereof to prevent the escape of bobbins from the belt, the space between said parts being but little more than the diameter of a bobbin; one of said parts being a belt, means for discharging bobbins from the other part onto the 80 first mentioned belt, and means for moving the belts.

38. A winder having, in combination, devices for supporting two thread containers, one of which is a spool and the other a bobbin, means for finding the loose end on the bobbin, means for carrying said loose end adjacent to a loose end on the spool; and means for uniting said two loose ends.

39. A winder having, in combination, a 90 support for spools and bobbins; means for causing said support to travel; means for winding the thread from the bobbins onto the spools; and means for doffing the bobbins as they pass a certain point.

40. A winder having, in combination, a support for spools and bobbins; means for causing said support to travel; means for uniting the threads from bobbins to the threads from spools; means for doffing filled 100 spools; and means for doffing the bobbins as they pass a certain point.

41. A winder having, in combination, devices for supporting a series of winding couples, and means for applying to said 105 supporting devices full supplying containers and empty receiving containers.

42. A spooler having, in combination, a series of vertical spool-spindles, a series of supports adapted rotatably to support warp 110 bobbins during the unwinding of yarn therefrom, means for rotating the spools to revolve the bobbins in the unwinding direction, means for removing full spools from the spindles, and means for placing 115 empty spools on the spindles.

43. A winder having, in combination, means for supporting a plurality of containers arranged in pairs; means for uniting the threads of each pair of containers; 120 means for actuating one container of each pair to cause yarn to be wound thereon; means for doffing one of each pair of containers; and means for doffing the other container of each pair when it contains a determined amount of yarn.

44. A winder having, in combination, a frame; means for supporting a plurality of spools and a plurality of bobbins on said frame; means for causing movement of said 125

75

supporting means; means for uniting the threads from bobbins to the threads of spools; means for doffing the bobbins; and means for doffing the spools.

5. 45. A winder having, in combination, a frame having an endless carrier thereon; means for driving said carrier; thread container supports carried by said carrier; means for uniting threads from certain of 10 said containers to threads from the other containers; means for rotating the containers upon which the yarn is to be wound; and means for doffing all of said containers.

46. The combination of a bobbin receptacle; means for releasing the foremost bobbin; means for rotating the released bobbin; a brush contacting with the surface of the rotating bobbin to brush up or find the thread end; means for holding the 20 found end; and means for ejecting the bobbin after the thread end has been found.

47. The combination of a bobbin receptacle; means for releasing the foremost bobbin; rotatable bobbin-end-engaging-means; 25 means for moving the bobbin-end-engaging-means into and out of engaging position with the released bobbin; a brush to contact with the surface of the rotating bobbin to brush up or find the loose end of the yarn; and 30 means for holding the found end.

48. A winder having, in combination, a series of traveling winding couple supports, endless belts for rotating the receiving member of each couple; and means for actuating said belts at varying speeds with respect to each other.

49. The combination, with a winder, of means for doffing thread containers, and means for sorting the doffed thread containers according to the amount of yarn thereon.

50. The combination with a doffer for thread containers, of means for sorting the doffed containers according to the amount 45 of yarn thereon.

51. A winder having, in combination, a bobbin-holder for rotatably supporting a full warp bobbin during the unwinding of 50 yarn therefrom, and a bobbin-grasping device arranged to grasp an empty bobbin and withdraw it from the bobbin-holder.

52. In combination, a series of bobbin supports; a bobbin-removing device; means for reciprocating said device in a right line 55 toward and from said bobbin supports; and means for producing a relative traveling movement between the supports and the bobbin-removing device to position the latter adjacent to successive supports.

60. 53. In apparatus for operating upon bobbins, in combination, a plurality of bobbin supports, a bobbin-engaging means comprising a plurality of relatively movable grasping members, means for producing 65 relative traveling movement between the

bobbin-engaging means and the plurality of bobbin supports, and means for reciprocating the bobbin-engaging means in a straight line toward and away from the bobbin supports.

70 54. The combination, with a vibratory support for shaking a mass of bobbins, of means for discharging measured quantities of full bobbins onto said support; and means to receive bobbins from said support.

75 55. The combination, with a vibratory support for shaking a mass of bobbins, of means for discharging bobbins on said support, and bobbin-controlled means for actuating said discharging means.

80 56. A winder having, in combination, a series of supply-bobbin supports, means to effect the discharge of spent bobbins from the supports, and means for causing relative traveling movement between the series of 85 bobbin supports and said discharging means.

85 57. The combination of a table, a bobbin-moving belt extending along one edge of the table for receiving bobbins from the 90 table, said table being arranged to discharge bobbins onto said belt, a bar extending along said belt, means for moving said bar toward and away from said belt, approaching movement of the bar being limited when a 95 bobbin is on the belt, and means controlled by the extent of approaching movement of the bar for delivering bobbins to the table.

100 58. The combination of an inclined table, a bobbin-moving belt extending along the lower edge of the table, and a gage bar extending longitudinally of and above the belt, said bar having an upwardly extending longitudinal flange at the side adjacent to the table.

105 59. The combination of a table, a bobbin-moving belt extending along one edge of the table for receiving bobbins from the table, said table being arranged to discharge bobbins onto said belt, a feeler for detecting 110 the presence of bobbins on the belt, and means controlled by said feeler for delivering bobbins to said table.

115 60. A winder having, in combination, a framework, a series of thread-container supports arranged to travel around the framework, a moving belt to make contact with and rotate the containers, and a relatively-stationary member arranged to engage successive supports for moving the containers 120 out of contact with the belt.

125 61. A spooler having, in combination, a traveling series of vertically-reciprocable slotted thread guides, and a relatively-stationary cleaning member arranged to enter the slots of successive guides when the guides are at a certain point in their path of vertical reciprocation.

130 62. The combination of a table, a bobbin-moving belt extending along one edge of

- the table, said table being arranged to discharge bobbins onto said belt, and a feeler bar extending longitudinally of and above the belt.
- 5 63. The combination of a bobbin-supporting table, and a bobbin-alining and moving means comprising a belt extending along one edge of the table, said table being arranged to discharge bobbins onto said belt.
- 10 the width of the belt being less than the length of a bobbin, a backing at the edge of the belt opposite to the table, and a bobbin-feeler supported adjacent the belt.
- 15 64. A bobbin-end sorter having a tortuous bobbin passage through which a bobbin may pass downward laterally, and means at the discharge end of said passage providing two outlets each smaller than the butt of the bobbin and larger than the tip
- 20 20 of the bobbin, whereby the butt of the bobbin will be retarded until the tip thereof has swung downward.
- 25 65. The combination of a bobbin receptacle, an inclined vibratory table, means for discharging bobbins from the receptacle onto the table, a bobbin-alining and conveying means at the lower edge of the table, a bobbin-end receiving bobbins from said alining and conveying means, an end-finding means receiving bobbins from said bobbin-end, a spooler having bobbin holders and spool supports, means for placing in said holders bobbins on which ends have been found, and mechanisms for uniting the 30 found ends to ends on the spools.
- 35 66. The combination of means for arranging full bobbins end to end; means for arranging the bobbins with certain ends all extending in the same direction; and means for finding the loose thread ends upon the bobbins.
- 40 67. The combination of an endless winding-couple carrier, replenishing mechanisms located adjacent to the path of movement of the carrier, and means for moving the carrier.
- 45 68. The combination of a framework providing an endless path of movement, a series of winding-couple supporting means on said framework, replenishing mechanism, and means for causing relative traveling movement between said series and said mechanism, around said framework.
- 50 69. A winder having, in combination, a stationary knotted, means for supporting a plurality of bobbins, and an endless movable chain for moving to said knotted the ends of threads extending from the bobbins, said chain being provided with means for attaching threads thereto.
- 55 70. The combination with a winder, of means for supplying filled thread containers thereto; and mechanism for uniting the threads on said containers to threads on 55 containers mounted on the spooler.
71. The combination with a winder adapted to have yarn masses mounted thereon, of mechanism for sorting bobbins in a determined order; means for finding the loose thread ends on the sorted bobbins; means for placing the bobbins on the winder; and mechanism for joining said thread ends to thread ends on said yarn masses.
- 75 72. The combination with a winder, of mechanism for supplying full bobbins and empty receiving containers thereto; and mechanism for doffing the filled receiving containers and empty bobbins therefrom.
- 80 73. The combination with a winder, of means for supplying a full thread container thereto; and means for doffing said container after the thread has been unwound therefrom.
- 85 74. A winder having, in combination, a yarn-mass support which is movable into and out of operative position; a thread-feeler for the thread being wound on the yarn mass; a device controlled by the feeler for moving the support out of operative position; and means for causing relative traveling movement between the yarn mass on the one hand and the feeler and said device on the other hand.
- 90 75. A winder having, in combination, a bobbin-holder comprising a cradle upon which a warp bobbin may be rotatably supported, a back-stop, and two side guards arranged to lie in contact with opposite sides of the yarn mass on the bobbin, and means for leading the bobbin thread under one of said guards.
- 95 76. The combination with a textile machine having supports thereon for thread containers, of doffing mechanism; and means for giving said thread containers and said doffing mechanism a relative traveling movement, said doffing mechanism being arranged to gage the amount of thread on said containers and to doff the containers of a certain size.
- 100 77. The combination with a spooler having supports thereon for spools, of doffing mechanism; and means for giving said supports and said doffing mechanism a relative traveling movement, said doffing mechanism being arranged to doff the spools during such travel.
- 105 78. A winder having in combination, a thread-container support, means to cause said support to travel, a throw-out member yieldingly located in the path of said support, and means to lock said member against yielding movement.
- 110 79. A winder having in combination, supports for thread containers; means for causing said supports to travel; and a doffing mechanism arranged to gage the amount of thread wound on the containers and to doff certain of the containers during their travel.

80. In a machine for winding thread from one container onto another, the combination of means for traveling a series of thread containers; and stationary doffing means.
- 5 81. The combination with a winder having a series of thread container supports, of independently mounted means for automatically lubricating such supports.
- 10 82. The combination with a spooler having a plurality of spool spindles thereon, of independently mounted means for automatically lubricating said spindles.
- 15 83. The combination with a winder having a series of thread container supports thereon, of means for lubricating said supports when there is no thread container thereon, said lubricating means being held from actuation by the thread containers on said supports.
- 20 84. A spooler having, in combination, a plurality of spool-supporting spindles; and means for lubricating said spindles, said means being held from operation when a spool is on a spindle.
- 25 85. The combination with a spooler having a series of spool spindles thereon, of means for doffing spools from said spindles; and means for lubricating the spindles after the spools have been doffed.
- 30 86. A winder having, in combination, a series of thread container supports; means for causing said supports to travel; means for placing thread containers on said supports; means for doffing said containers; and means between said doffing means and said placing means for lubricating said supports.
- 35 87. A winder having, in combination, a thread-container support, means to cause said support to travel, a throw-out member yieldingly located in the path of said support, and means to lock said member against yielding movement, said locking means being withdrawable through contact with a thread.
- 40 88. The combination of a knotter, means for moving thread ends to the knotter, and an endless flexible member, a portion of which is arranged to extend to and past the knotter for moving one of said threads.
- 45 89. The combination of a knotter, a device for clamping two thread ends and moving them to the knotter, and means at each side of the knotter, each arranged to engage a single one of the threads for moving said threads toward each other and into the knotter.
- 50 90. The combination of a knotter, means for moving two thread ends to the knotter, and a device at each side of the knotter, each arranged to engage a single one of the threads for moving said threads toward each other and into the knotter, said devices also serving to move the united threads past the knotter.
- 55 91. The combination of a knotter, means for moving two thread ends to the knotter, and an endless flexible member at each side of the knotter, each arranged to engage one of the threads for moving said threads to the knotter.
- 60 92. Textile apparatus comprising, in combination, means for arranging in a tier and in substantial parallelism thread containers from which thread is to be unwound, and means for thereafter sorting said containers so that similar ends extend in the same direction.
- 65 93. A winder having, in combination, a series of thread-container supports, a belt arranged for contact with yarn masses mounted on said supports for rotating said yarn masses, a member located adjacent to said belt and also arranged for contact with said yarn masses, and means for causing relative movement between the series of spindles and said member, for rotating the yarn masses.
- 70 94. A winder having, in combination, a framework, a series of thread-container supports arranged to travel around the framework, means at one end of the framework for moving the supports out of operative position, a member located at one end of said means and arranged for contact with the peripheries of yarn masses mounted on said supports, and a belt located adjacent to said member and also arranged for contact with the peripheries of said yarn masses for rotating the latter, said supports moving out of engagement with said means, then into contact with said member, and thereafter into contact with said belt.
- 75 95. A winder having, in combination, a framework, a series of spool spindles and bobbin supports arranged to travel around the framework, a stationary knotter for uniting the threads of bobbins and spools, and means for taking up slack in the united threads.
- 80 96. A winder having, in combination, a framework, a series of spool spindles and bobbin supports arranged to travel around the framework, a stationary knotter for uniting the threads of bobbins and spools, and a stationary member with which the spools make contact after passing the knotter for rotating the spools to take up slack in the united threads.
- 85 97. A winder having, in combination, a bobbin-holder comprising a support on which a warp bobbin may be rotatably supported, and two side guards arranged to lie in contact with the yarn mass on the bobbin, and means for longitudinally inserting a warp bobbin into the space between said side guards.
- 90 98. The combination of a hopper for bobbins, an inclined vibratory table arranged beneath said hopper, an endless belt con-

veyer extending along the lower edge of said table, the width of said conveyer being less than the length of a bobbin, and a bobbin-ender arranged to receive bobbins from said conveyer.

5 99. The combination of a hopper for bobbins, sorting means arranged to receive bobbins from said hopper, valve means controlling the discharge of bobbins from said hopper, and means depending upon the presence or absence of bobbins at said sorting means for controlling said valve means.

10 100. The combination of a hopper for thread containers, a magazine arranged to receive containers from said hopper, and adapted to support a tier of containers arranged side by side, and mechanism controlled by the containers in said magazine for regulating the discharge of containers from said hopper.

15 101. A winder having, in combination, a yieldable throw-out cam-member, a yieldable yarn-container support arranged to travel into contact with the cam-member, and a movable thread feeler for locking said member against yielding movement and for unlocking said member, the movement of the feeler serving to unlock the cam-member to movement into inoperative position under

20 30 the pressure of the support.

102. A winder having, in combination, a bobbin holder, means for supporting and rotating a yarn mass, a yarn-mass-rotating plate interposed between the yarn mass and the rotating means, and means for causing relative movement between the supporting means and said plate in a direction at substantially a right angle to the axis of the yarn mass, the yarn mass passing from the plate directly into contact with the rotating means.

25 103. A winder having, in combination, a stationary knotter having a tying bill and thread-guides at each side of the bill, a movable thread-carrier to support a series of threads, and means to cause a portion of each thread to extend transversely of the direction of movement of the carrier, the tying bill and guides being located in the path of movement of such transverse thread-portions.

35 104. A winder having a stationary knotter, a member movable toward the knotter, a clamp on said member to hold the end of a thread, a device near the knotter to move the thread into position to enter the knotter, and means near the knotter to open the clamp.

40 105. A bobbin-end sorter having two outlets each smaller than the butt of the bobbin and larger than the tip of the bobbin, whereby the butt of the bobbin will be retarded until the tip thereof has swung downward.

106. The combination of a bobbin-ender

5 having a tortuous passage through which the bobbins descend by gravity, and means to arrange the bobbins in definite order and to deliver them into the upper end of said passage.

107. The combination of a bobbin-ender having a tortuous passageway through which the bobbins descend by gravity, and means arranged to align bobbins end to end and deliver them into the upper end of said passageway.

15 108. The combination of a bobbin-ender having a tortuous passageway through which the bobbins descend by gravity, bobbin-alining means arranged to deliver the bobbins into the upper end of said passageway, and a conveyer arranged beneath the bobbin-ender to receive bobbins therefrom.

20 109. Textile apparatus comprising, in combination, a magazine for thread containers, means to deliver containers into the upper end of said magazine, and means at the lower portion of the magazine for finding loose thread ends on said containers.

25 110. Textile apparatus comprising, in combination, means for finding loose thread ends on thread-containers, a guide for a series of thread-containers, and means for successively presenting to said thread-finding means the lowermost containers in said guide.

30 35 111. Textile apparatus comprising, in combination, means for finding loose thread ends on a thread container, a guide through which a row of thread containers may descend by gravity, and means arranged to take the lowermost thread container in said guide, present it to said end-finding means, and remove it therefrom when the end has been found.

40 45 112. In a textile machine, means for finding the loose end upon a thread container comprising means for rotating the container and a rotary brush rotating in the same direction as said means and arranged to contact the periphery of the thread on said container to brush up the loose end.

50 55 113. End-finding means for textile machines, comprising means for rotating a thread container, means for brushing up the loose thread-end thereon, and means to receive and hold the found end.

55 60 114. End-finding means for textile apparatus comprising a rotary brush, means adjacent thereto for rotating a thread container, and means for successively presenting thread containers to said rotating means.

65 70 115. A textile machine having, in combination, means for picking up the loose end upon a thread container, and a suction air tube arranged to receive and hold the picked-up end.

75 80 116. A textile machine having in combination means for holding a series of thread containers, means for picking up thread ends, an oscillatory device arranged to suc-

130

cessively present the containers to said picking-up means, and a suction air tube arranged to receive and hold the pick-up end.

5 117. End-finding means comprising a rotary brush, and mechanism for moving a thread container into contact with said brush and for rotating said container.

10 118. The combination with a winder, of means for supplying full thread containers thereto, and means for finding the loose thread ends on said containers.

15 119. The combination with a winder having a series of bobbin holders, of means for supplying full bobbins to said holders, and means for finding the loose thread ends on said bobbins.

20 120. The combination with a spooling machine having a traveling series of spool and bobbin supports, of stationary means for supplying full bobbins to said bobbin supports, and means for finding the loose thread ends on the bobbins.

25 121. A winder having, in combination, a thread-container support, a carrier for the support, means for causing said carrier to travel, and means located in the path of the support for engaging and moving the latter out of operative position.

30 122. A winder having in combination, a side delivery bobbin-holder for rotatably supporting a bobbin during the unwinding of yarn therefrom, means for rewinding yarn from the bobbin contained in said holder, a bobbin-supporting device adjacent to the bobbin holder, and means to effect a discharge of the bobbin from the bobbin-supporting device to the bobbin holder.

35 123. A textile machine having, in combination, stationary thread-uniting mechanism, and traveling air suction means arranged to present threads to said uniting mechanism.

40 124. A textile machine having, in combination, thread-uniting mechanism, and air suction means arranged to carry the threads to be united to said uniting mechanism.

45 125. A textile machine having, in combination, thread-uniting mechanism, movable means having an opening therein, and means for creating a suction of air into said opening to draw a thread thereinto, said movable means being arranged to carry the threads to be united into operative association with said thread-uniting mechanism.

50 126. A textile machine having, in combination, winding mechanism, including a series of traveling pairs of thread-container supports, stationary thread-uniting mechanism past which said supports are carried, and means to present the threads from a pair of containers to said uniting mechanism.

55 127. A winder having, in combination, a series of traveling supports for pairs of

thread containers, a stationary thread-uniting mechanism past which said supports are carried, and traveling means for presenting the threads of a pair of containers to said uniting mechanism.

70 128. A winder having, in combination, a series of traveling supports for thread containers, and a thread-uniting mechanism past which said supports travel, said uniting mechanism being arranged to unite the threads of two thread containers.

75 129. A spooler having, in combination, a series of traveling supports for spools and bobbins, a thread-uniting mechanism past which said supports travel, and means for presenting threads from a bobbin and a spool to said thread-uniting mechanism.

80 130. A spooler having, in combination, an endless traveling carrier, spool supports and bobbin supports mounted on said carrier, a thread-uniting mechanism past which said supports travel, and means for presenting the threads from a bobbin and a spool to said uniting mechanism.

85 131. A winder having, in combination, 90 winding mechanism including an endless series of traveling supports for spools and bobbins, means for supplying bobbins to their supports, and mechanism arranged to join the thread of a newly supplied bobbin 95 to the thread of a spool.

132. A winder having, in combination, an endless carrier having thereon a series of supports for spools and bobbins, means for finding the thread end on a bobbin, and mechanism arranged to join the found end to the thread on a spool.

100 133. A winder having, in combination, a framework, an endless carrier mounted thereon, a series of supports for spools and bobbins mounted on said carrier, relatively stationary means for supplying full bobbins to their supports, relatively stationary thread-uniting mechanism, and means for presenting threads from a newly supplied bobbin and a spool to said uniting mechanism.

105 134. A winder having, in combination, a framework, an endless carrier mounted thereon, a series of supports for spools and bobbins mounted on said carrier, relatively stationary means for supplying full bobbins to their supports, means for finding the loose thread ends on said bobbins, a relatively stationary thread-uniting mechanism, and means arranged to present threads from a newly supplied bobbin and a spool to said thread-uniting mechanism.

115 135. A winder having, in combination, 125 winding mechanism including an endless series of traveling supports for spools and bobbins, and relatively stationary mechanism for joining the thread from a bobbin to the thread from a spool.

130 136. A winder having, in combination, a

- side delivery bobbin-holder for rotatably supporting a bobbin during the unwinding of yarn therefrom, means for rewinding yarn from the bobbin contained in said holder, a device adapted to contain a bobbin and from which a bobbin may gravitate, a member preventing gravitational movement of the bobbin, and means to cause said member to be withdrawn whereby the bobbin is permitted to gravitate into the bobbin holder. 137. Textile apparatus comprising, in combination, means for supporting a thread, means for operating on the thread, and a suction air tube including a portion which is longitudinally movable with relation to the remainder of the tube, said portion being arranged to carry the thread to said operating means. 138. A textile apparatus comprising, in combination, means for supporting a thread, means for operating on the thread, and a suction air tube including an endless chain forming a longitudinal wall of the tube, said chain having openings therein to receive the thread and convey it to said operating means. 139. The combination of a bobbin holder, a device adapted to contain a bobbin and from which a bobbin may gravitate, a member preventing gravitational movement of the bobbin, said member being arranged for engagement with the bobbin holder, and means for causing relative movement between the bobbin holder and the bobbin containing device whereby said member is engaged by the bobbin holder and withdrawn from operative position. 140. The combination of a bobbin holder, a thread-end holder above the bobbin holder, and mechanism for placing a bobbin in the bobbin holder and for placing the end of the thread on the bobbin in said thread-end holder. 141. A winder having, in combination, winding mechanism, including a traveling series of spool and bobbin supports, a relatively stationary thread-uniting mechanism, and a suction device including an endless moving portion arranged to convey the threads from a bobbin and a spool to said uniting mechanism. 142. A winder having, in combination, means for causing a series of spools and bobbins to move in a prescribed path, and relatively stationary means for doffing the bobbins. 143. A winder having, in combination, an endless carrier, a series of spool and bobbin supports mounted on said carrier, and relatively stationary means arranged to grasp a bobbin and withdraw it from its support. 144. A winder having, in combination, an endless series of bobbin pockets in which the bobbins lie, means for causing said series to travel, and stationary means for withdrawing the bobbins from their pockets. 145. A winder having, in combination, a series of supports for full bobbins from which thread is to be unwound, means for causing said supports to travel, means for doffing the bobbins from their supports, and means for sorting the doffed bobbins according to the amount of yarn thereon. 146. In combination with a winder having a series of bobbin pockets thereon, means for doffing the bobbins from their pockets, and means for sorting the doffed bobbins according to the amount of yarn thereon. 147. In combination with a winder having a series of supports for thread containers, means for doffing the containers from their supports, and means for sorting the doffed containers according to the amount of thread thereon. 148. The combination with a winder having a series of bobbin pockets in which the bobbins lie, of means arranged to positively engage the bobbins and remove them from their pockets. 149. The combination with a winder having a series of bobbin pockets in which the full bobbins lie, of means arranged to grasp the bobbins after thread has been unwound therefrom, and withdraw the bobbins from their pockets. 150. The combination with a winder having a traveling series of bobbin pockets, of means arranged to advance and engage the tips of successive bobbins in their pockets and withdraw the bobbins therefrom. 151. In a machine for winding threads from one container onto another, the combination of means for causing a series of thread-container supports to travel, and stationary means for doffing the thread containers from their supports. 152. The combination with a winder having a series of traveling pairs of supports for thread containers, of relatively stationary means for successively doffing one thread container of each pair. 153. In a machine for winding thread, the combination of a series of substantially upright spindles, means for causing said series of spindles to travel, and relatively stationary means for doffing the containers from said spindles. 154. In a winding machine, the combination of means for causing a series of thread containers to travel, and a pair of endless doffing devices between which the thread containers are carried. 155. In a textile machine, the combination of a pair of endless doffing belts, and means for successively moving thread containers.

- tainers through the space between said belts.
156. A winder having, in combination, a series of spindles arranged to hold thread containers, means for causing said spindles to travel, and a pair of endless belts between which the spindles travel, said belts being arranged to engage the thread containers on said spindles and remove them therefrom.
157. A winder having, in combination, a series of substantially vertical spindles arranged to support thread containers, means for causing said spindles to travel, and a pair of endless doffing belts between which the spindles pass, said belts being inclined in the direction of travel of the spindles, and being arranged to remove the thread containers therefrom during the travel of the spindles.
158. A textile machine having, in combination, means for supporting a thread container, and a pair of endless traveling devices lying at opposite sides of said container, and arranged to engage the same to remove it from its support.
159. A textile machine having, in combination, a series of traveling supports for thread containers, and means for removing said containers from their supports, said means being adapted to remove only containers that have attained a certain size and to permit smaller containers to pass.
160. A spooler having, in combination, a series of traveling supports for spools, and means for doffing the spools, said means permitting the spools to pass when they have less than a certain amount of thread thereon.
161. A winder having, in combination, a series of container-supporting spindles, means for winding thread on the containers, and a single means arranged to select containers having a predetermined amount of thread thereon and to doff such containers from their spindles.
162. A spooler having, in combination, stationary lubricating means, and means for causing a series of spool supporting spindles to travel past said lubricating means, the latter being arranged to be held from actuation when a spindle has a spool thereon.
163. A winder having, in combination, a support for a thread container, and means controlled by the presence or absence of a container on said support for applying a lubricant to said support.
164. The combination in a textile machine, of a series of supports for thread containers, and means controlled by the presence or absence of containers on their supports for successively lubricating said supports.
165. A winder having, in combination, a support for a thread container, means for doffing the container from said support, and means for lubricating said support.
166. A winder having, in combination, a spindle arranged to support a spool, means for doffing the spool from the spindle, and means for subsequently applying a lubricant to said spindle.
167. A winder having, in combination, a spindle arranged to support a spool, means for doffing the spool from the spindle, means for then applying a lubricant to the spindle, and means for subsequently placing another spool upon said spindle.
168. A winder having, in combination, a series of traveling spindles, means for applying a spool to a spindle, means for winding thread upon the spool, means for doffing the full spool, and means between the doffing means and said applying means for lubricating the spindle.
169. A winder having, in combination, a series of spindles, a guide arranged to direct thread containers onto said spindles, means for causing a relative movement between said series of spindles and said guide, and means controlling the passage of containers along said guide and arranged to prevent the application of a container to a spindle having a container thereon.
170. A winder having, in combination, an endless series of traveling spindles, a stationary guide arranged to direct thread containers onto said spindles successively, and means controlling the passage of containers along said guide and arranged to detect the presence of a container on one of said spindles and prevent the application of another container thereto.
171. A winder having, in combination, a series of thread container supports, selectively-acting means for doffing certain of the containers from their supports, and arranged to permit the other containers to go undoffed, and selectively-acting means for supplying containers only to those supports which are empty.
172. A winder having, in combination, a series of supports for thread containers, means for doffing containers having a certain amount of thread thereon, and arranged to permit containers having a less amount of thread to pass without being doffed, and mechanism governed by the presence or absence of containers on said supports for supplying containers to those supports from which containers have been doffed.
173. The combination of a series of bobbin pockets, means for withdrawing empty bobbins from the pockets, and other means for supplying full bobbins to the pockets.
174. The combination of a bobbin holder, means for placing a bobbin in said holder, a member arranged to engage a thread ex-

- tending from the bobbin and draw said thread upwardly, a member arranged to take the thread from the first mentioned member and move the thread laterally, and a thread end holder to which the thread is moved by the second mentioned member.
175. The combination of a thread-guide having a thread-receiving space therein, a yieldingly mounted cleaning blade arranged to enter and clean said space, and means for causing relative approaching movement between the thread-guide and said member.
176. The combination with mechanism for winding thread, of mechanism for automatically supplying thread containers to and removing them from the winding mechanism, and mechanism arranged to unite the thread end on a newly supplied container to the thread end on a container carried by the winding mechanism.
177. The combination with mechanism for winding thread, of means for supplying thread containers thereto, means for removing thread containers therefrom, and means for uniting the thread ends on newly supplied containers to the thread ends on containers carried by the winding mechanism.
178. A winder having, in combination, means for automatically supplying full thread containers, means for automatically supplying empty thread containers, and mechanism for winding the thread from the full containers onto the empty containers.
179. A winder having, in combination, means for supplying both full and empty thread containers, means for removing both full and the empty containers, and mechanism for winding the thread from the full containers onto the empty ones.
180. A winder having, in combination, means for winding thread from one container onto another, means for supplying full containers, means for supplying empty containers, means for removing full containers, means for removing empty containers, and means arranged to join the thread end from a newly supplied full container to a thread end on a container carried by the winding means.
181. In combination, a yarn mass receptacle; means for discharging the foremost yarn mass from the receptacle; rotatable yarn mass engaging means; means for moving the engaging means into and out of position to engage the discharged yarn mass; and a brush to contact with the surface of the yarn mass.
182. The combination of means for supporting by its ends a carrier having yarn wound thereon, an end finder to find the end of the yarn, and means for causing relative surface movement between the carrier and the end finder in a direction transverse to the longitudinal axis of the carrier.
183. In a textile machine, in combination, a table arranged to receive bobbins, said table being inclined so that the bobbins will roll or slide therefrom, and means for retarding bobbins which have yarn thereon.
184. In a textile machine, in combination, a table arranged to receive bobbins, said table being inclined so that the bobbins will roll or slide therefrom, and means to engage bobbins having yarn thereon and cause them to pass in a certain direction off the table.
185. In a textile machine, in combination, a table arranged to receive bobbins, said table being inclined so that the bobbins will roll or slide therefrom, and friction means arranged to retard bobbins having yarn thereon and cause them to pass from the table in a certain direction.
186. In a textile machine, in combination, an inclined table, means to place bobbins thereon, and means on the table to cause the separation of entirely empty bobbins and bobbins having thread thereon.
187. In a textile machine, in combination, an inclined table from which bobbins may roll or slide, and means to retard the sliding of bobbins from the table and thus cause the separation of entirely empty bobbins and bobbins having thread thereon.
188. In a textile machine, in combination, means to effect the separation of entirely empty bobbins and bobbins having thread thereon, means for delivering bobbins thereto, and a pair of diverging belts onto which the bobbins containing thread are directed.
189. In a textile machine, in combination, an inclined element from which thread containers may roll or slide, and means arranged to engage thread containers having thread thereon and cause them to pass from said element in a certain direction.
190. In a textile machine, in combination, an inclined element from which thread containers may roll or slide, and a friction element arranged to engage thread containers having thread thereon and cause them to pass from the table in a certain direction.
191. In a textile machine, in combination, a table inclined in two directions and adapted to receive thread containers, and a friction element adjacent to said table for guiding the movement of containers which have thread thereon so as to effect a separation of such containers from entirely empty containers.
192. The combination of means for holding a carrier having yarn wound thereon, an end finder to find the end of the yarn, means for causing surface movement of one of said parts (namely, the carrier and the end finder) in a direction transverse to the longitudinal axis of the carrier, and means for causing the carrier to rotate to unwind the yarn.

193. The combination of a frame for holding carriers having yarn wound thereon, a chute to deliver carriers to said frame, an end finder to act upon and find the end of the yarn, and means for moving said frame to transfer carriers to and from the end-finder.

194. The combination of means for holding a yarn carrier for surface movement transversely of its longitudinal axis, and a brush for acting upon the yarn during such surface movement to find the end of the yarn and cause the same to be unwound from the carrier during such surface movement.

195. A receptacle for receiving bobbins provided with tips and heads, the heads of some of the bobbins being in alinement with

the tips of adjacent bobbins, and means for selecting the tip of each bobbin irrespective of the position of the bobbin and causing said tip to be passed foremost through the receptacle.

196. A winder having, in combination, a stationary knotter, a series of bobbin supports, a series of clamps for the threads of the bobbins, a member for moving a thread into proximity to the knotter, and means for moving said bobbin supports and clamps to bring threads successively within reach of said member.

HOWARD D. COLMAN.

BURT A. PETERSON,
LOUISE A. CULVER.

Corrections in Letters Patent No. 1,227,754.

It is hereby certified that in Letters Patent No. 1,227,754, granted May 29, 1917, upon the application of Howard D. Colman, of Rockford, Illinois, for an improvement in "Winders," errors appear in the printed specification requiring correction as follows: Page 11, line 101, for the word "extended" read *extruded*; page 12, line 68, for the word "rest" read *rests*; page 15, line 12, claim 29, before the word "means" insert the words *spool spindles carried by said carriers*; and that the said Letters Patent should be read with these corrections therein that the same may conform to the record of the case in the Patent Office.

Signed and sealed this 26th day of June, A. D., 1917.
